GOLF PUTTER HEAD

Joseph Frederick Rango, 2126 W. 177th St.,
Torrance, Calif. 90504

Filed Jan. 6, 1970, Ser. No. 20,784

Term of patent 14 years

Int. Cl. D21—01

U.S. Cl. D34—5

FIG. 1

FIG. 2

FIG. 3

FIG. 4

FIG. 5

FIG. 6

FIG. 7

FIG. 1 is a perspective view of a golf putter head showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof; and,

FIG. 7 is a side elevational view thereof.

I claim:

The ornamental design for a golf putter head, substantially as shown.
